US0D1104428S

(12) **United States Design Patent** (10) **Patent No.:** **US D1,104,428 S**
(45) **Date of Patent:** **** Dec. 9, 2025**

(54) **SHOE**

(71) Applicant: **adidas AG**, Herzogenaurach (DE)
(72) Inventors: **Strahinja Spasic**, Los Angeles, CA (US); **Robert Stinchcomb**, Chestertown, NY (US); **Arnaud Sanjuan Roman**, Brooklyn, NY (US); **Baptiste Jacques Dany Tarenne**, Fuerth (DE); **Benjamin Alexander Thompsett**, Nuremberg (DE)

(73) Assignee: **adidas AG**, Herzogenaurach (DE)

(**) Term: **15 Years**

(21) Appl. No.: **29/966,583**

(22) Filed: **Oct. 3, 2024**

Related U.S. Application Data

(63) Continuation of application No. 29/871,063, filed on Feb. 10, 2023, now Pat. No. Des. 1,050,697.

CLAIM

The ornamental design for a shoe as shown and described.

DESCRIPTION

FIG. 1 is a top front isometric view of a shoe showing the claimed design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines in the figures show portions of the shoe that form no part of the claimed design.

1 Claim, 7 Drawing Sheets
